J. G. LORENZ

SHANK FOR EAVES TROUGH HANGERS

Filed Oct. 6, 1923

UNITED STATES PATENT OFFICE.

JOHN G. LORENZ, OF PHILADELPHIA, PENNSYLVANIA, ASSIGNOR TO UNITED ALLOY STEEL CORPORATION, OF CANTON, OHIO, A CORPORATION OF NEW YORK.

SHANK FOR EAVES-TROUGH HANGERS.

Application filed October 6, 1923. Serial No. 666,941.

To all whom it may concern:

Be it known that I, JOHN G. LORENZ, a citizen of the United States, residing at Philadelphia, in the county of Philadelphia and State of Pennsylvania, have invented certain new and useful Improvements in Shanks for Eaves-Trough Hangers, of which the following is a specification.

This invention relates to hangers or supports for eaves-troughs or gutters, and especially to a shank for supporting the gutter-hanger circle; and the objects of the improvement are to provide a one-piece shank to which the gutter-hanger circle may be connected in any desired position of vertical adjustment.

The shanks or supports at present in common use for an upright surface, are comprised of two parts, riveted or otherwise connected together. Shanks of this character not only limit the adjustment of the gutter-hanger circle, but they are more expensive to manufacture and have less durability than the present one-piece shank.

The invention is illustrated in the accompanying drawing, in which—

Fig. 1 is a side elevation of the improved shank illustrating a minimum adjustment as may be obtained for a gutter-hanger circle carried thereby;

Fig. 2, a similar view showing a maximum adjustment of the circle;

Fig. 3, a front elevation of the shank with the circle in the position shown in Fig. 1;

Fig. 4, a detail perspective view of the shank; and

Fig. 5, a fragmentary view of a modified form.

Similar numerals refer to similar parts throughout the drawing.

The shank to which the invention pertains is an integral structure which may be cast or otherwise formed, and comprises the attaching plate 1 provided with apertures 2 in each end portion thereof for the reception of nails, screws or other fastening means.

The stem 3 of the shank is located substantially at the vertical center of the attaching plate and depends a considerable distance below the same. The stem comprises the integral vertical rib 4 formed upon the front face of the attaching plate, at right

angles to the normal plane thereof and extending downward therefrom

The inner edge of the rib 4 is provided with an angular flange 5 which may be a continuation of the attaching plate 1, and a similar flange 6 is provided at the outer edge of the rib.

The stem thus comprises a vertical channel and throughout practically its entire length it is apertured transversely as at 7, whereby a gutter-hanger circle of well known design, designated at 8, may be adjustably secured thereto at any point throughout its length as by the bolt 9.

Since the stem and plate are formed in an integral structure, it is apparent that the stem may be apertured entirely from end to end to permit vertical adjustment of the gutter-hanger circle at any point throughout its entire length, as the means necessary for connecting the stem and connecting plate are not present.

With this construction, the gutter-hanger circle may be connected at the extreme upper end of the stem as shown in Fig. 2, locating the same in close juxtaposition to the eaves of a building if desired.

From the above, it will be obvious that the advantages of the present construction consist not only in providing for a maximum adjustment of the gutter-hanger circle throughout the entire length of the stem of the shank, but the same provides means for locating the gutter in closer to the building to which it is attached than is possible with the two part shank in which the stem is connected to the outer face of the attaching plate, while at the same time a more durable and substantial structure is provided.

For the purpose of freely cleaning the connected end of the gutter-hanger circle, the attaching plate may be slightly offset upon the flange 5 of the shank as shown in the modified form of parts illustrated in Fig. 5; without departing from the spirit of the invention.

I claim:

1. A shank for eaves-trough hangers comprising a stem channel shaped and apertured throughout its length for the adjustable connection of a gutter-hanger circle, and an integral attaching plate upon the upper end

of the stem, in the plane of one of the channel flanges.

2. A shank for eaves-trough hangers comprising an attaching plate having a central integral channel stem extending vertically across its front face and depending therefrom at right angles thereto, said stem being channel shaped throughout its length.
- 5 3. A shank for eaves-trough hangers comprising an attaching plate having a central, integral channel stem extending vertically across its front face and depending there-
- 10

from at right angles thereto, said stem being channel shaped from end to end and said rib being apertured throughout its length.

15 4. A shank for eaves-trough hangers comprising an attaching plate having a central, integral channel stem extending vertically across its front face and depending therefrom, said rib being apertured throughout 20 its length, and vertical flanges at the front and rear edges of the stem.

JOHN G. LORENZ.
